DESIGN FOR A TINNER'S FURNACE

Percy M. Forster, Berkeley, Calif.

Application September 30, 1940, Serial No. 95,529

Term of patent 3½ years

To all whom it may concern:

Be it known that I, Percy M. Forster, a citizen of the United States, residing at the city of Berkeley, county of Alameda, State of California, have invented a new, original, and ornamental Design for a Tinner's Furnace, of which the following is a specification, reference being had to the accompanying drawing, forming part thereof.

Fig. 1 is a perspective view of a tinner's furnace showing my new design;

Fig. 2 is a top plan view thereof;
Fig. 3 is a side elevational view thereof;
Fig. 4 is an elevational view of one end thereof;
and

Fig. 5 is an elevational view of the opposite end.

I claim:

The ornamental design for a tinner's furnace, substantially as shown.

PERCY M. FORSTER.
